UNITED STATES PATENT OFFICE.

JAMES B. ANDERSON, OF PORTLAND, OREGON.

HYDROAEROPLANE.

1,420,606.

Specification of Letters Patent. Patented June 20, 1922.

Application filed August 26, 1920. Serial No. 406,063.

To all whom it may concern:

Be it known that I, JAMES BRUSH ANDERSON, a citizen of the United States, and a resident of Portland, county of Multnomah,

5 State of Oregon, have invented a new and useful Improvement in Hydroaeroplanes, of which the following is a specification.

My invention has for its object the providing of a device which may be converted 10 into an aeroplane or hydroplane in an instant; that is to say by the mere operation of a lever and a pedal, or similar devices at the pilot's station.

To this end my device comprises both 15 running wheels, and a pontoon; the former serving when my device is to be used as an aeroplane, and the latter when to be used as a hydroplane. In other words my device is changed from an aeroplane to hydroplane 20 by lowering the pontoon and raising the running gear above the water line; and it is changed from hydroplane to an aeroplane by lowering the wheels and raising the pontoon; the devices controlling the wheels and 25 the pontoon operating in unison, so that the lowering of one and the raising of the others will be simultaneous.

Furthermore the fuselage is so designed 30 that the front part thereof constitutes a water tight compartment.

Other features of my invention will be brought out in the detailed description thereof hereinafter contained.

In the accompanying drawings, Fig. 1 35 shows a side elevation of my device as a whole;

Fig. 2 shows a partial longitudinal vertical section, of the fuselage, also showing means provided for raising and lowering 40 the running wheels and the pontoon; in this view my device is assumed to have been arranged for use as a hydroplane;

Fig. 3 shows a front elevation of my device as it appears when arranged as an aeroplane;

Fig. 4 shows a transverse section taken 45 on the plane of the broken line 4 of Fig. 2, illustrating the control of the means provided in the front part of the fuselage for releasing the wheel lock so that the wheels 50 may be raised for converting my device into a hydroplane;

Fig. 5 is a transverse section taken on the

plane of the broken line 5 of Fig. 2, and illustrating the construction of the wheel-frame, and the shock absorbing feature thereof;

Fig. 6 shows a transverse section taken on the plane of the broken line 6 of Fig. 2, and 60 illustrates the means provided for effecting the simultaneous lowering of the wheels while raising the pontoon, and vice versa;

Fig. 7 shows a transverse section on the plane of the broken line 7 of Fig. 2, and 65 illustrates the keeper provided for holding the pontoon in its down or active position, said keeper being also cooperatively connected with said raising and lowering means;

Fig. 8 shows an inner face elevation on the plane of the broken line 8 of Fig. 5, and 70 illustrates the shock absorbing element of the wheel-frame;

Fig. 9 shows a sectional detail illustrating the wheel-frame lock; that is devices holding the wheel-frame in its active or down position, and also illustrates the auxiliary shock absorbing means included in the wheel frame;

Figs. 10, 11 and 12, show a related group of details of the means provided for slidably holding the braces of the wheel-frame so that the latter may be adjusted into either its down or up positions, or in other words 85 its active and inactive positions; thus Fig. 10 shows a perspective of one of the sliding blocks to which the upper ends of the braces of the wheel frame are fastened; Fig. 11 shows one of the guides in which said blocks 90 slide; and Fig. 12, which is drawn partly in section, illustrates the shock absorber element included in said blocks;

Fig. 13 shows a perspective sectional detail of one of the rear double wall portions 95 of the fuselage, between which the pontoon is hinged; and

Fig. 14 is a detail of means for operating the drums on which are wound the cables attached to the wheel frame and to the pontoon.

My device comprises fuselage or body of rectangular cross section the front part consisting of single walls, and the rear part of double or hollow walls as at α' (see Fig. 13) 100 with the bottom open between the walls, and between these hollow wall portions is hinged 105

the pontoon *b*. The purpose of making the rear side walls *a'* double is two fold, namely; to brace the rear wall portions, and at the same time to provide an air chamber contributing towards the buoyancy of the device when afloat in the water.

10 The front part of the fuselage is divided from the rear portion by a wall-and-floor partition *c* as illustrated in Fig. 2, and the front part of the fuselage is adapted to constitute a water tight compartment when the hatch *d* is closed.

15 The walls of the front compartment of the fuselage are provided with windows *e* at the sides and also in front. At the point where the pontoon *b* is hinged between the side walls *a'* the latter are reinforced by plates *b* at the inner sides.

20 The fuselage is provided with wheels *f* which are journaled on a wheel-frame *g* (see Fig. 5), said wheel-frame including an axle *g'* and braces *h*. The bottom of the front section of the fuselage is provided with a recess *i* to receive the axle *g'* when the wheel-frame is thrown in its up or inactive position. The braces *h* of the wheel frame are attached at their upper ends to lateral pins *j* borne by blocks *k* (see Fig. 12), which slide in guides *m*. The blocks *k* are provided 25 with pins *n* which bear reciprocably in a smaller block *l*, and springs *o* are inserted between the blocks *k*, *l*. Latched blocks *p* are adapted for being projected in front of the blocks *l* as shown in Fig. 9. The latched 30 blocks *p* are carried on bars *q* which have a sliding bearing in brackets *r* fastened to the exterior of the fuselage. The bars *q* are made with eyes *s*, and to the latter are attached cables *t*, which enter the sides of the 35 fuselage, and are connected to an arm of the foot-lever *v*, by the operation of which the latch-blocks *p* may be withdrawn from in front of the blocks *l*. When withdrawn, the wheel-frame may be arranged in its inactive 40 position; and when the wheel-frame is arranged in its active position the springs *w* (see Fig. 9) will project the latch-blocks *p* as shown in Fig. 9, thereby locking the wheel-frame in its active position. And 45 when the wheel-frame is so locked the blocks *k* and *l* with the connecting pins and coil springs *o* mounted thereon will constitute shock absorbers.

50 The wheel-frame is also adapted to have a vertical movement against the springs *3*, or, in other words, is provided with a further shock absorbing element illustrated in Figs. 2, 5 and 8. The ends of the upper cross-piece *g²* of the wheel-frame are journaled in boxes *x* which slide in guides *y* as shown in Fig. 8 more clearly; the boxes are provided with pins *z* which slide in brackets 55 *2*, and the boxes *x* bear against said coil springs *3*.

60 65 The wheel-frame is raised and lowered by

means of cables *4* which extend into the interior of the fuselage and are fastened to and wind on the larger drums *5*; the latter being fast on an axle *6* and on the latter is also rigidly mounted a pin *7* meshing with a gear segment *8* (shown in Fig. 14) having an arm *10* to which the cable *11* is attached, the other end of which cable being fastened to a lever *12*. See Figs. 2 and 14. Thus by pulling the lever *12* in one direction the gear segment is rotated thereby revolving the drum axle *6* and when the lever *12* is released, the gear segment *8* is rotated in the opposite direction by the reaction of the spring *13*, thus winding and unwinding the cables *4* and lifting or lowering or in other words placing in inactive or active position the wheel-frame *g*.

70 The pontoon *b* is raised and lowered by a cable *14* which winds on the middle drum *15* carried by said axle *6*. The connection of the pontoon *b* and the wheel-frame *g* through the medium of said cables with the drums carried by the shaft *6* is such as to cause the rotation of said shaft *6* in one or the other 75 direction either to lower the wheel-frame and lift the pontoon or vice versa. The pontoon is limited in its downward motion by a stop *16* shown in Fig. 2 and the pontoon is locked in its down or active position by a latch arm *17* connected by a cable *18* with a cable *14*, the cables being so arranged that in the operation of said drums to lift the pontoon the latch arm *17* will be moved out of the way in advance of the lifting of the 80 pontoon *b* by the cable *14*. On the forward part of the fuselage is mounted the wing supporting frame *18* which may be of any convenient construction; *19* represent the wings of the usual construction, *20* represent a pair of pusher type propellers which are rotated by motors *21*. At the ends of the wings are provided pontoons *22* of the 85 usual type.

90 For the convenience of shipping my device I prefer to detachably fasten the wing frame by bolts or otherwise on the fuselage and to sustain the same in place by stay cables *23*.

95 At the tail end of the fuselage is provided a supplemental ground wheel *24*. *25* represents a rudder element of the usual type but placed higher than in the usual type of aeroplanes so as to provide suitable clearance from the water, when my device is used as a 100 hydroplane. The rudder element is understood to be operated by suitable appliances arranged as convenient and therefore not illustrated.

105 I do not of course limit myself to the exact details of construction above described.

I claim:

110 1. In a hydroaeroplane a fuselage adapted to constitute a cabin completely enclosed in the forward part and having rearwardly ex-

tending hollow side wall portions, and a pontoon hinged between such wall portions and adapted to be raised there-between.

2. In a hydroaeroplane, the combination of 5 fuselage running wheels journaled on an adjustable frame carried by the fuselage, a pontoon hinged to the latter, and means for lifting the wheel-frame while lowering the 10 pontoon, and vice versa, the fuselage being curved upward forward of the wheel-frame, and the rear part of the fuselage sloping upward at an angle, and comprising side wall portion spaced apart, between which the 15 pontoon is carried.
3. In a hydroaeroplane, the combination of 20 fuselage running wheels journaled on an adjustable frame carried by the fuselage, a pontoon hinged to the latter, and means for lifting the wheel-frame while lowering the 25 pontoon, and vice versa, the fuselage being curved upward forward of the wheel-frame, and the rear part of the fuselage sloping upward at an angle, and comprising side wall portion spaced apart, between which the 30 pontoon is carried, and a supporting wheel provided at the rear end of the fuselage.

4. A hydroplane comprising a fuselage, 35 running wheels journaled on adjustable frame carried by the fuselage, a pontoon hinged to the latter, a hoisting element, and controlling means therefor located at the 40 pilot station in the fuselage, cables connecting 45 said wheel-frame and said pontoon with said hoisting element, the latter being adapted to wind up one of said cables when unwinding the other, and means for locking said pontoon in its active position.

said hoisting element, the latter being adapted to wind up one of said cables when unwinding the other.

5. A hydroplane comprising a fuselage, 35 running wheels journaled on adjustable frame carried by the fuselage, a pontoon hinged to the latter, a hoisting element, and 40 controlling means therefor located at the pilot station in the fuselage, cables connecting 45 said wheel-frame and said pontoon with said hoisting element, the latter being adapted to wind up one of said cables when unwinding the other, and means for locking said pontoon in its active position.

6. A hydroplane comprising a fuselage, 50 running wheels journaled on adjustable frame carried by the fuselage, a pontoon hinged to the latter, a hoisting element, and 55 controlling means therefor located at the pilot station in the fuselage, cables connecting said wheel-frame and said pontoon with said hoisting element, the latter being adapted to wind up one of said cables when unwinding the other, and means for locking 60 said pontoon in its active position, said means being operated by a cable also connected to said hoisting element the latter cable being so operated as to apply said locking means after the pontoon has been lowered into its active position, and to withdraw said locking means in advance of the lifting of the pontoon.

JAMES B. ANDERSON.
